UNITED STATES PATENT OFFICE

1,929,025

BAGLESS VACUUM CLEANER

Ward Leathers, Haworth, N. J., assignor to The Quadrex Corporation, a corporation of Connecticut

Application August 2, 1930, Serial No. 472,703
Renewed March 1, 1933.

4 Claims. (Cl. 183—36)

The object of my invention is to produce vacuum cleaners without the dirt bag commonly used. In order to accomplish this purpose I have invented new means of filtering the exhaust air, of 5 catching the dirt in a receptacle, and of locating the same in suitable and novel places.

In the following description I have set forth the possibilities involved in my invention and have appended thereto, for purposes of clarity, 10 drawings in which

Fig. 1 is a side view of a vacuum cleaner
Fig. 2 is the same

Fig. 3 is a cross-section of handle filter and dirt container

15 Fig. 4 is a cross-section of modified handle filter

Fig. 5 is a front elevation of a hollow yoke providing double air exhaust

Fig. 6 is a side view of vacuum cleaner with 20 parallel filter

Fig. 7 is a modified double air exhaust

Fig. 8 is a cross-section of same

Fig. 9 is an attaching device

Fig. 10 is a handle.

25 In Figure 1 I have shown a conventional vacuum cleaner for light or heavy duty, depending upon size, in which 1 is the motor case, 2 is the blower case, 3 is the nozzle case. It is usual practice with rotary blowers to take the exhaust

30 from a spiral enlargement at the periphery of the rotor. I have taken the exhaust from the rotor in the conventional manner, except that I have used two outlets, 4 and 5, on opposite sides of the blower case. These are taken off spirally in 35 the direction of rotation and turned around in such manner that the two exhausts turn toward each other immediately back of the blower case. Connected to these outlets 4 and 5, in a hinged manner, is a hollow air conductor 6 provided with

40 exhaust ducts shown at 7 (see Fig. 7). At the top of 6 there is an enlarged portion 8, to the bottom side of which is latched, or fastened, the dirt receptacle 9 and to the top side of which is attached the handle 10. 11 is a hook for holding 45 the electric cord. 12 is the same. 12 may be folded into the handle 13. At 14 I have shown a tightly closed door 14, hinged at 15, released by a latch at 16, the purpose of which is to permit instantaneous cleaning of the filter in the handle by means of the blast from the blower itself.

50 If the filter is in the handle 10 it is obvious that the household user can drop the handle out an open window while the motor is running, release any suitable latch 16, and the door 14 will be blown open and the filter cleaned.

In Figure 2 I have shown a similar arrangement of air-duct, handle filter and dirt receptacle, except that the exhaust ducts from the blower casting, extensions 4 and 5, continue their separation to the top of the dirt receptacle 9 instead of being 60 joined together as in Figure 1 (see Fig. 5).

Figure 3, the upper portion 8 of the hollow yoke bracket 6, is shown in cross-section. Air from the blower comes up through the passage 17 and is deflected downward by a baffle 18, after which it 65 continues its travel upward through the hollow handle 10. The baffle is for the purpose of deflecting heavier objects and particles directly into the dirt receptacle 9 instead of permitting their entrance into the handle filter. The dirt receptacle 9 may be made of any suitable material and in any suitable shape and attached to 8 in any desirable manner. I have shown it in a preferable form, made of transparent material such as cel- 70 luloid, equipped at its top with a metal rim 19, this 75 metal rim is provided with a very steep thread 20 which engages a similar thread in the casting 8, said thread being so steep that a partial turn of the receptacle 9, such as 45° will release or engage said thread. The handle 21 is rigidly attached 80 to the rim 19 and thereby provides simple means of manually attaching and detaching the dirt receptacle 9 from the machine.

The filter handle may be provided with its filter elements on the outside (Fig. 3) or on the 85 inside (Fig. 4). In Figure 3, 22 is a hollow tube, preferably of thin-walled hard fibre, about 1½ inches in diameter. 22 is provided with ports 23 in any desired size, number and arrangement, and is attached to 8 in suitable manner (shown 90 with screw thread), and at the top to a suitable handle top as 24 in Figure 1. The hollow tube 22 is then covered with any suitable filter material. It may be a specially woven porous material, or a felt-like material or preferably a velvet shown 95 at 25. This material must be of a highly porous character. It may be put on the tube 22 reasonably tight or reasonably loose as is required for permitting the air to creep beneath it and escape over its entire area rather than through only 100 those areas in juxtaposition to the ports. The filter cover 25 is fastened at both ends in any suitable manner. I have shown it sewn to a metal ring 26 and anchored by a threaded collar 27. 105

In Figure 4 I have shown a similar handle filter modified by placing the filter elements inside the perforated tube 22. The porous element 28 may be of any suitable material, such as felt or velvet. In the latter case the nap is naturally turned out 110

toward the tube 22 to permit the air to escape from the inside duct, over its entire area, finding its way through the nap to the ports 23. Another means of permitting the use of the entire filter area is to sew the fabric or filter material into tubular form, slightly smaller than the inside diameter of the perforated tube 22. A still further method of using thin filter material, such as silk, consists of a thin open mesh screen 29, 5 to the inside face of which is sewn a filter lining 28 as shown by the stitches at 30. This combination of screen and other filter material, such as silk fabric, may be used as a unit and slid inside of the tube 22 and fastened at both ends in 10 any suitable manner, such as the ring and clamp method shown at 31.

Figure 5 is a front view of a hollow yoke bracket 6 (as in Figure 2.) It may be entirely of one casting as shown at 6 in Figure 2 or the portions 20 7 and 8 may, for purposes of easier manufacture, be separated by tubular or other shaped duct parts 32.

In Figure 6 I have shown a conventional 25 vacuum cleaner with an air-duct yoke-bracket slightly rearranged. The air from the part 6 is carried directly into the handle 10 with no communication with the dirt-receptacle 9. The handle 10 consists of a plain hollow tube of metal or hard fibre. At the top of the handle 10 I 30 have provided a housing member 33 to which 10 is attached in suitable manner as well as the handle 13. The blast of air from 10 is turned about within 33 in a suitably formed cavity 34 so that it may exhaust downward into an exposed filter 35. 35 consists of a sleeve or hose of highly porous material. Air and dirt enter its upper portion at 36 and the dirt exhausts from its lower portion at 37 into the dirt-receptacle 9 which is supported by 8, a part of the hollow duct-yoke 6. 40 This is a highly desirable arrangement for high duty purposes because it gives the maximum of air volume and filtration, and a continuous movement of the dirt through the filter aided by both air and gravity. 38 is a stout reinforcement 45 sewn around the filter tube 35 and provided with a suitable clip whereby it is anchored to the handle 10.

Figure 7 is a back view of the part 6.

Figure 8 is a cross-section of the part 6 in Figure 7.

Figure 9 illustrates one of many suitable means of attaching the filter tube 35 to the end-holders 34 and 8. The filter tube in this case is sewn at 39 to a stouter piece of fabric which is again 55 sewn fast to a spiral-spring shown by the dotted lines. At the top of the spiral-spring there is a ring developed from the spring itself by means of which attachment is made to 34 by a clamp ring 40, stouter fabric over the spring covers it 60 completely inside or outside and is sewn to the top ring. The spring mechanism may be used or not as desired, but its object is to provide some slight elasticity to the filter tube 35 since in handling the vacuum cleaner with the motor not running the tube 35 may be collapsed against the handle 10.

Figure 10 shows a hollow yoke 41 for the same purpose as the lower portion of 6 in Figures 1-2 and 6. It is attached directly to the handle 70

10 which is provided with inside or outside filter as in Figures 3 and 4. The handle 13 is provided with a rubber bumper 42 and the latch 14 for the same purpose as in Figure 1. For light duty vacuum cleaners such a filter handle is 80 highly practical without the dirt receptacle 9 of Figures 1-2 and 6 because the handle 10 will hold sufficient dirt still permitting of proper filtration for sweeping an ordinary small room or two under normal conditions, and the user may, 85 immediately upon completing such operation, drop the handle end of the vacuum cleaner out an open window or into a suitable receptacle, release the latch 14, and instantly and completely free the vacuum cleaner of all dirt. 14 90 may be on the end of 13, a location corresponding to 42.

Having set forth my invention in terms understandable by all, I wish it understood that the principles involved in this invention are applicable in many ways and by many types of design to the vacuum cleaner industry, in the hands of those skilled in these arts.

I claim:—

1. In a suction cleaner, a motor-blower unit, 100 a perforated hollow handle, filtering material disposed substantially the entire length and area of said handle, a manually removable dirt receptacle operably attached to the bottom of said handle for retrieving dirt from said handle by gravity, and an air duct leading from the outlet of said motor-blower unit to a juncture with the bottom end of said filter handle but above said dirt receptacle.

2. In a suction cleaner, a motor-blower unit, 105 a perforated hollow handle, filtering material disposed substantially the entire length and area of said handle, a manually removable dirt receptacle operably attached to the bottom of said handle for retrieving dirt from said handle by 115 gravity, an air duct leading from the outlet of said motor-blower unit to a juncture with the bottom of said filter handle but above said dirt receptacle, and with said air duct so operably 120 joined to the motor-blower unit that it may be 125 angularly moved with respect thereto.

3. In a suction cleaner, a motor-blower unit, 125 a perforated hollow handle, filtering material disposed substantially the entire length and area of said handle, a manually removable dirt receptacle operably attached to the bottom of said handle for retrieving dirt from said handle by gravity, an air duct leading from the outlet of said motor-blower to a juncture with the bottom 130 end of said filter handle but above said dirt receptacle, and with a manually operated valve at the top of said handle for the purposes set forth.

4. In a suction cleaner, a motor-blower-unit, 135 a hollow handle, a tube of filtering material disposed parallel to and substantially the entire length of said handle, means of leading dirt-laden air to the bottom of said hollow handle and delivering said dirt-laden air to the top of said filter tube, and with the bottom of said filter 140 tube communicating with a manually removable dirt receptacle.

WARD LEATHERS.
